UNITED STATES PATENT OFFICE

HERMAN H. KOLLER, OF AMSTERDAM, NEW YORK

ROLLER SHADE

Application filed July 25, 1932. Serial No. 624,611.

This invention relates to roller shades, and has more particular reference to the type of roller shade embodying a plurality of slats and capable of being wound and unwound relative to a suitable roller provided therefor, such a shade being, as is well known used either for windows or porches.

My invention relates to an improved type of roller shade together with improved means for mounting the same and for actuating the roller thereof, and the invention will be best understood from a study of the following description, taken in connection with the accompanying drawings wherein:

15 Figure 1 is a front elevational view of the shade, the same being shown applied to a window and in a fully lowered or unwound condition.

Figure 2 is a longitudinal sectional view 20 thereof the lower portion of the shade being shown in an angular position for ventilating purposes.

Figure 3 is a fragmentary vertical sectional elevational view taken through a window 25 having my shade applied thereto and showing the spring actuated drum for winding and unwinding the shade forming part of the invention.

Figure 4 is a fragmentary horizontal sectional view looking downwardly on the structure shown in Figure 3.

Figure 5 is a vertical sectional view through a portion of a modified form of shade.

Figure 6 is a fragmentary perspective view 35 showing the manner of securing one end of a slat to a tape.

Figure 7 is a perspective view of a tape section to be hereinafter more fully referred to.

40 Figures 8, 9 and 10 are fragmentary longitudinal sectional views through additional forms of the shade.

Figure 11 is a side elevation of one form of mounting for the spring drum, and

45 Figure 12 is an elevational view illustrating the manner of internally mounting the winding drum.

Referring more in detail to the drawings it will be seen that 10 designates generally 50 a window casing having side members 11 and

top member 12. Suitably mounted at the outer side of the window 13 are opposed parallel channel members 14 connected at their upper ends by spaced parallel horizontal strips 15 and at their lower ends by a channel member 16. The channel members 14 and connecting strips 15 are braced relative to one another by corner plates 17, while the channel members 14 and 16 are braced relative to one another by similar corner 60 plates 18.

The channel members 14 adjacent their upper ends are separated transversely to provide relatively rigid fixed upper sections 14a and swingable lower sections 14b connected 65 to the sections 14a by suitable hinges 19.

Constrained to slide between the guides 14 is a flexible shade designated generally by the reference character 20. As is common to all forms of the invention the shade 20 comprises 70 a plurality of slats flexibly connected by two spaced flexible tapes 21. The shade 20 is windable on a roller 22 rotatably mounted in the upper window frame member 12, the upper ends of the tapes 21 being secured to the 75 roller 22 as clearly suggested in Figure 2.

The roller 22 on one end thereof is provided with a spool 23 on which is windable a tape or other flexible element 24. Tape 24 is also windable on a drum 25 that is provided with internal spring mechanism 25' and ratchet means (not shown) whereby the drum 25 is caused to normally rotate in one direction and is readily released for rotation in a reverse direction, the type of drum being of 85 a well known form.

In the present instance the drum is rotatably mounted on a stub shaft 26 carried by a bracket 27 adapted to be arranged in a pocket 28 provided therefor in one side 11 of a 90 window frame adjacent the lower end of said side. Carried by one end of the bracket 27 is a face plate 29 for closing the open side of the pocket 28 as shown in Figures 3, 4 and 12, and this plate 29 is bolted to the window 95 frame or otherwise secured thereto as at 30. The tape 24 is passed through a sleeve 31 lining an opening provided therefor in the frame member 12 as shown in Figure 2 and also through an inclined sleeve. Obviously 100

- from the description of the invention thus far it will be apparent that by pulling on the tape 24 drum 25 may be released for rotating in one direction, and through the tape 24 transmitting the movement of the roller 22 for winding the shade 20 thereon, or for rotating in an opposite direction to transmit, through the tape 24 movement to the roller 22 for unwinding the shade 20 as may be found desirable.
- 10 When desired the lower portion of the shade 20 engaged with the channel sections 14b may be swung out to the position shown in Figure 2 for ventilating purposes, and to this end, and for holding the lower sections 15 14b of the channel members in the position shown in Figure 2 foldable braces 33 are provided, the braces as is obvious, being pivotally connected at one end with the channel sections 14b and at their other ends pivotally connected to the blind stops as indicated generally at 34.

In each form of shade the slats thereof are provided with notches 35 for receiving the tapes 21, and fastening elements such as 25 shown at 36 in Figure 6 and 36a in Figure 10 are used to connect the tapes with the slats. Further, in the form of the invention shown in Figure 1 the slats are arranged as to have their longitudinal beveled edges contact one 30 with the other as clearly shown in Figure 2. In the form of the invention shown in Figure 5 the slats are slightly spaced for ventilating purposes. In the form of the invention shown in Figure 8 the beveled edges of the 35 slats are also formed to provide grooves 37 and tongues 38 for engaging the grooves.

In the form of the invention shown in Figure 9 instead of the longitudinal edges of the slats being beveled, said edges are formed to 40 provide tongues 39 and grooves 40 for receiving the tongues as shown.

In the form of the invention shown in Figure 10 the slats are similar to the form of slats shown in Figure 8, however in this form of 45 the invention instead of having the tapes 21 continuous, said tape consists of a plurality of sections 41, each section 41 shown in Figure 7 being provided at its ends with elongated slots 42, and as shown in Figure 10 the slots 50 42 accommodate the securing or fastening screws 36a in a manner to provide a pin and slot connection between the ends of the tape section 41 and the slats.

I have also shown in Figure 11 a modified form of mounting for the drum 25, the form of mounting shown in said figure being especially adapted for mounting the drum upon the window frame in a manner clearly visible, and without necessitating the pro-

viding of the pocket 28 as in the mounting of the drum as shown in Figures 3 and 4. The mounting shown in Figure 11 may be termed an outside mounting and comprises a base plate 43 to which is secured the ends of a 70 bracket 44, which bracket 44 and plate 43 supports therebetween a stub shaft 45 on which the drum 25 is journaled. The upper end of the bracket 44 also has formed integral therewith a guide mouth or spout 46 through 75 which the tape passes as shown.

Even though I have herein shown and described the preferred embodiment of the invention, it is to be understood that the same is susceptible of further changes, modifications and improvements coming within the scope of the appended claims.

Having thus described my invention, what I claim as new is:

1. In a roller shade, the combination of a 85 shade, a roller on which the shade is windable, and operating means for the roller comprising a face plate having a tubular tape guide projecting therefrom, drum supporting means on one face of the plate, a spring drum mounted in said supporting means, a spool on the roller, and a tape passing through said guide and having its end portions windable on said drum and spool and respectively connected thereto.

2. In combination, a face plate, a bracket mounted thereon, a spring drum supported by the bracket, a tubular tape guide mounted in operative position to said drum, and a tape windable on the drum and passing through 100 said guide.

3. A roller mount comprising a face plate, a drum supporting bracket extending from the back side of the plate at right angles thereto, and a tubular tape guide projecting 105 from the front side of the plate.

4. A drum mount comprising a face plate provided with means thereon to support a drum, and a tubular tape guide mounted on one side of the plate.

5. A roller mount comprising a face plate, a drum supporting bracket on the front face of the plate and a tubular tape guide mounted on the bracket.

6. In a drum mount, a drum supporting 115 bracket, a tubular tape guide, and a face plate supporting said bracket and said guide.

7. As a new article of manufacture, a unitary structure consisting of a face plate having a tubular tape guide projecting outwardly therefrom.

In testimony whereof I affix my signature.

HERMAN H. KOLLER.
